DESIGN FOR A PIZZA PIE OVEN

Arthur I. Fader, Yonkers, and Ira Nevin,
Bronx, N. Y.

Application May 12, 1947, Serial No. 138,996

Term of patent 3½ years

(Cl. D81—10)

To all whom it may concern:

Be it known that we, Arthur I. Fader and Ira Nevin, both citizens of the United States, residing at Yonkers and the Bronx, New York, in the counties of Westchester and Bronx and both in the State of New York, have invented a new, original, and ornamental Design for a Pizza Pie Oven, of which the following is a specification, reference being had to the accompanying drawing, forming a part thereof.

In the drawing:

Fig. 1 is a perspective view of a pizza pie oven, showing our new design;

Fig. 2 is a top plan view; and

Fig. 3 is a side elevational view of the same.

The side of the pizza pie oven, not shown, is like the side shown in Figs. 1 and 3.

We claim:

The ornamental design for a pizza pie oven, as shown and described.

ARTHUR I. FADER.
IRA NEVIN.
